UNITED STATES PATENT OFFICE

SAMUEL M. TAYLOR, OF LOYALTON, CALIFORNIA, ASSIGNOR TO SMOOTH SAW EQUIPMENT COMPANY, OF LOYALTON, CALIFORNIA, A CORPORATION OF NEVADA

TOOTH SWAGE

Application filed March 7, 1931. Serial No. 520,822.

This invention relates to a tooth swage which is more particularly adapted to swage the planer teeth of a saw blade such as illustrated in my copending application Serial No. 505,745, filed December 31, 1930.

It is the principal object of this invention to provide a swaging tool which will swage the face of a planer tooth of a saw blade such as illustrated in my copending application above referred to, for substantially the full depth of the said tooth.

It is a further object of this invention to provide a swaging tool which will evenly swage the face of the planer tooth above referred to for substantially the entire depth of said tooth.

It is a further object of this invention to provide a swaging tool which will perform the swaging operation by a rolling action.

It is a further object of this invention to provide a swaging tool with means for forcing the die of said swage along the cutting face of the planer tooth and simultaneously rotating the swaging die.

It is a further object of this invention to provide a cylindrical die for a swaging tool with a substantially flattened portion to permit the face of the tooth to be swaged to be presented to the said flattened portion of

said die so when the die is rotated the cylindrical portion thereof will force its way into the face of the tooth and cause the metal displaced thereby to flow laterally to form an upset or swage and thence to draw and simultaneously rotate the die along the face of the tooth, thereby causing the metal displaced by the die to be rolled or forced to flow laterally an equal amount to each side of the tooth from the bottom to the top

thereof.

It is a further object of this invention to provide means for adjusting the amount of swaging action that is to be performed per operation of the swage.

It is a further object of this invention to provide means for adjusting the degree of angle with which the flattened portion of the swaging die makes with the face of the tooth to thereby adjust the amount of swaging action of said die.

It is a further object of the invention to provide means for adjusting the relation of the swaging tool to the face of the tooth so that the swaging die will be drawn along the face of the tooth in a plane substantially parallel thereto.

It is a further object of this invention to provide a swaging tool with an anvil which rests upon the top of the tooth to prevent said tooth at the completion of the swaging operation from being swaged above the plane normal to the top thereof.

It is a further object of this invention to provide a means for clamping the saw blade during the swaging operation.

Other objects and advantages of this invention will become apparent as the nature of the same is more fully understood from the following description and accompanying drawings, wherein is set forth which is now considered to be a preferred embodiment. It should be understood, however, that this particular embodiment of the invention is chosen principally for the purpose of exemplification, and that variations therefrom in details of construction or arrangement of parts may accordingly be effected and yet remain within the spirit and scope of the invention as the same is set forth in the appended claims.

In the drawings:
Figure 1 is a perspective view of the invention.

Figure 2 is a sectional view taken substantially along the center line of the tool.

Figure 3 is a sectional view taken substantially along line 3-3 of Figure 2 looking in the direction of the arrows.

Figure 4 is a partial sectional view taken substantially along line 4-4 of Figure 2 of the reciprocating die carrying block and a portion of the anvil.

Figure 5 is an enlarged diagrammatical view illustrating the die in the position it would occupy when adjusted to make a maximum swage and at the starting point of the swaging operation.

Figure 6 is a diagrammatic view similar to Figure 5, excepting that the swaging die

has been rotated substantially a quarter turn.

Figure 7 is a diagrammatic view similar to Figures 5 and 6 excepting that the die has been operated to substantially complete the swaging operation.

Figure 8 is a partial top view of the saw blade illustrating two teeth which have been swaged and a third tooth which has not as yet been swaged.

Figure 9 is a fragmentary perspective view illustrating the rack and pinion arrangement for initially rotating the die and sliding the die-carrier with relation to the swage block.

In the drawings, the block or base 1 is provided with a longitudinal slot 2 through which the saw 3, partially shown in dotted lines in Figure 3, is adapted to pass. The saw blade is usually held fast in a saw vise or by any suitable means, not shown, while the swage block 1 is moved from tooth to tooth of the saw. In order to clamp the swage block 1 to the saw blade during the swaging operation, the rear portion of slot 2 is enlarged to receive at one side thereof a suitable fixed clamp block 4 which may be secured in place by any suitable means while opposite to clamp block 4 is a movable clamp block 5 which is slidably mounted upon pins 5a and is normally held retracted from contacting with saw blade 3 by a spring means 6 comprising a headed screw 7 screw threaded into the movable clamp block 5 as at 8 and slidably extending through the side wall of block 1, at which point block 1 is counterbored to receive spring 9. When the swage block has been placed in operative position it is essential to securely clamp block 1 to the saw blade and to accomplish the clamping operation, the movable clamping block 5 is forced into and held in engagement with saw 3 by means of a jack screw 10 which is screw threaded through the side block 1, and to insure sufficient threads therefor block 1 is provided with a threaded boss 11.

A suitable handle 12 engages the head of jack screw 10. By rotating screw 10 by means of handle 12 the screw feeds through block 1 and engages the movable clamping block 5, forcing same into clamping engagement with the saw blade. To release the tool after the swaging operation has been completed the handle 12 is operated to withdraw the jack screw 10 from engagement with clamp block 5. With the release of pressure of screw 10 spring 9 acts through the headed screw 7 to retract the movable clamp block 5 out of engagement with saw blade 3. If desired, the clamping blocks 4 and 5 may be serrated so as to more securely grip the saw blade.

Near the forward end of block 1 there is provided a transverse slot 15 having slid-

ably mounted therein a die carrier block 16 which is provided with a slot 17 in line with slot 2 of base 1 to permit the entrance of saw 3 therein. Journaled in the die carrier block 16 and extending across slot 17 is the die rod 18 which is engaged adjacent each side of carrier block 16 by a bifurcated handle 19 and is secured to handle 19 by suitable means such as set screws 20, most clearly seen in Figures 1 and 2. By actuating handle 19 it will be noted that die rod 18 is rotated and to cause die rod 18 to move along face 21 of tooth 22 of saw 3, block 1 is provided at each side with fulcrum pins 23 which are positioned to be engaged by handle 19 after the handle has rotated die rod 18 a predetermined degree.

A further movement of handle 19 causes said handle to fulcrum about the fulcrum pins 23 and thereby forces die rod 18 and die carrier block 16 upward. The upward movement of die rod 18 is guided by the die carrier block 16 traversing slot 15. It should be noted that during this upward movement die rod 18 is simultaneously rotated.

It will be seen by referring to Figures 2, 3, 4, 5, 6 and 7 that the die rod 18 is cylindrical excepting that a portion of the cylindrical surface has been cut away as illustrated at 24. When the tool has been set to make the maximum swage, section 24 thereof coincides with face 21 of the tooth to be swaged, as is clearly seen by referring to Figure 5. This figure also illustrates in dotted lines the full circumference of the die or, in other words, the amount of cut or bite the die will make when forced through the swaging operation. Handle 19 is rotated until it engages fulcrum pins 23. This initial rotation of handle 19 rotates die 18 and, as illustrated in Figure 6, the flattened section of die 18 has been rotated until it no longer engages face 21 of the saw and as the saw was clamped securely so that it could not move away from the die, the cylindrical portion of the die has been rolled into the metal of the tooth, and consequently causing the metal to be displaced to each side of the tooth.

The die now has the required bite and it is necessary to move same along face 21 to the position of the die as indicated in Figure 7 to swage or flare the sides of the tooth. Handle 19 fulcrums about the fulcrum pins 23 during the secondary movement thereof to force die 18 and the die carrier 16 upward. During the secondary movement of handle 19, the carrier block 16 traverses slot 15 to guide the die 18 as it moves upward in a plane substantially parallel to face 21 of the tooth and so that after the die has been given the desired bite, the secondary rotation of handle 19 causes the die to carry the bite the full depth of the tooth, as is illustrated in Figure 7. As die 18 is secured to handle 19, said die

is rotated during the secondary rotation or movement of said handle. The rotation of the die during the swaging operation is an important feature of the invention, as it results in a better and more even flow of the displaced metal and also prevents cracking or tearing of the tooth being swaged and also prevents undue wearing or cutting of the swaging die.

10 The metal during the swaging and rolling action of the die flows equally to each side of the tooth, as illustrated in Figure 8. In this figure, 25 illustrates a tooth before swaging, while 26 and 27 illustrate teeth which have been swaged, and it will be noted that the metal displaced from face 21 of each tooth has been caused to flow equally to each side thereof.

15 In some saws it is desirable that the cutting edge of the planer teeth be given a 5 degree back angle. It is therefore necessary that die 18 also operate in a plane having a 5 degree back angle, or in a plane parallel to the plane of the face of the tooth to be swaged. In the present embodiment, the slot 15 in which slides the die carrier block 16 is formed in block 1 at a 5 degree angle from vertical, and for convenience the front face 41 of the block 1 is also made at 5 degrees from the vertical or parallel to slot 15. To enable the tool to be adjusted to swage teeth which have been formed with a different or no back angle, there is provided at the rear end of block 1 an adjustable angle block 31 clamped to said block by means of screw 32. To change the angle of the plane in which the die 18 traverses, screw 32 would be loosened and the angle block 31 shifted until the plane of action of die 18 coincides 20 with the plane of the teeth which are to be swaged.

25 To prevent the swaging die 18 from swaging or raising the upper edge of the teeth above the normal top plane of the teeth, an anvil 33 is provided, as will be clearly seen in Figures 2, 4, 5, 6 and 7. The anvil 33 is secured in slot 2 of block 1 by any suitable means such as by screw 34, and is provided with a projection 35 which is positioned at the 30 top of the tooth being swaged and prevents the metal of the tooth from being forced upward as die 18 approaches the upper edge thereof, as clearly illustrated in Figure 7.

35 It is often desirable to adjust the amount of swage or bite that the die will make for each operation. It will be appreciated by referring to Figure 5 that when the flattened portion 24 of die 18 coincides with the face 21 of the tooth that the maximum swage or 40 bite will be obtained and to reduce the swage or bite it is only necessary to rotate the flattened portion 24 of die 18 so that when the saw is clamped into position section 24 will be at an angle to the plane of the tooth. To 45 therefore adjust the angular relation of sec-

tion 24 to the face of the tooth to be swaged, a stop 36 is adjustably mounted upon the top of block 1 by means of cap screw 37 and washer 38. With the parts in position as illustrated in Figure 2 a maximum swage or bite would result, but by loosening screw 37 and moving the adjustable stop 36 toward the front of the tool, the angular portion of stop 36 will engage a portion of handle 19 and limit its rearward rotation, and as die 18 is secured thereto, the angular relation of the flattened section 24 will be adjusted with relation to face 21 of the tooth to be swaged.

50 If desired, hardened wearing plates may be inserted in each leg of handle 19, as illustrated at 40, in Figure 1, so that the contact of handle 19 against pins 23 will not unduly wear the handle 19 and so that should the plates 40 become worn they may be easily replaced.

55 The operation of the swage is briefly as follows:

60 The saw blade 3 is tightly clamped in the usual saw vise, not shown, the swage placed upon the top of the saw blade so that saw blade 3 extends through slot 2. The operator should first check the angular adjustment of the swage. For convenience in checking the angular adjustment of the swage, the front face 41 of block 1 is given 65 the same angle as slot 15, which represents the plane of travel of swaging die 18. Therefore, when face 41 is aligned with face 21 of the tooth to be swaged, the operator knows that the swaging die will operate in a 70 plane parallel to the face of the tooth and make an even swage along the face of the tooth. If the face 41 does not align with face 21 of the tooth the operator would 75 loosen screw 32 and adjust the stop 31 until face 41 of block 1 is in alignment with face 21 of the tooth. Next the operator should 80 adjust stop 36 to regulate the amount of swage to be given to the tooth. The position of stop 36 in Figure 2 illustrates the position of the 85 parts when the maximum swage is to be obtained. By adjusting stop 36 forwardly of the position illustrated in Figure 2, less swaging action will be obtained.

90 After the angular and swaging adjustments have been made, the swage is then ready for operation. The adjustable stop 31 and anvil 33 normally ride upon the top of saw blade teeth and as slot 2 of block 1 is somewhat wider than the thickness of the blade, the swage is free to be slid along the blade until the flattened portion 24 of the swaging die 18 engages face 21 of the tooth to be swaged. The saw is then tightly clamped by operating handle 12, as has been previously described. After the saw blade has been clamped the swaging operation is ready to be started. Handle 19 is rotated, rotating die 18 in the die carrier block 16 until the handle engages the fulcrum pins 23. Dur- 100

ing this initial rotation of handle 19, the flattened portion 24 is rotated from its position, as illustrated in Figure 5 to the position as illustrated in Figure 6, and it will be observed by comparing these two figures that by so rotating die 18, the cylindrical portion of die 18 is forced into face 21, causing the displaced metal to flow to the side of the tooth. This action gives the die its swaging bite.

It is now necessary to carry die 18 along face 21 with this bite to generate the desired swage.

Handle 19 is now further rotated and fulcrums about pins 23, thus rotating die 18 and forcing the die and die carrier 16 to travel upward along slot 15, and as slot 15 has been adjusted parallel to face 21, the die 18 rotatingly carries the bite along the face of the tooth until it reaches the position shown in Figure 7, where die 18 has just completed its swaging operation, and in this figure it will be noted that the displaced metal has been caused to flow to the side of the tooth evenly for the entire depth of the tooth and also that anvil 33 prevents the tooth from being swaged above the normal top surface of the tooth.

The swaging operation is now completed. The swage is unclamped by lever 12, handle 19 returned to its initial position, the swage shifted until the flattened portion 24 of die 18 engages face 21 of the next tooth to be swaged and the clamping and swaging operation repeated until all of the teeth of the saw blade have been swaged.

It should be understood that the angle and amount of swage having once been adjusted, that it is not necessary to change these adjustments for each tooth. One or many complete saw blades may be swaged after the angle and amount of swage have once been correctly adjusted.

As after repeated use of the swage the die 18 may become worn, therefore the flattened section 24 is made of considerable width so that die 18 may be shifted to present a fresh surface to the tooth.

It is to be understood that the initial rotation of the die and the subsequent rotation and travel of the die along the face of the tooth may be accomplished by a rack and pinion arrangement or other analogous means without departing from the spirit of this invention, and also the rotation of the swaging die may be in a counter-clockwise direction as viewed in the figure of the drawings instead of rotating in a clockwise direction.

In the modified form of the invention illustrated in Figure 9, block 50 is provided with a rack 51 while the operating handle 52 is provided with a mutilated pinion 53. By this rack and pinion arrangement, the operating handle may be first rotated to initially rotate the die 54 to take its bite into the tooth of the saw blade before the die is drawn along

the front face thereof; and, second, by a further rotation of the operating handle, the teeth of the mutilated pinion engage the rack 51 to force the die along the face of the tooth being swaged while simultaneously rotating the die. A rack and mutilated pinion may be provided at each side of block 50. In all other respects the swage as illustrated in Figure 9 is substantially identical to the swage illustrated in the other figures of the drawings.

It is understood that the embodiment of the invention described herein is only one of the many embodiments this invention may take, and I do not wish to be limited in the practice of the invention, nor in the claims, to the particular embodiment set forth.

I claim:

1. A tooth swage including the combination of a swage block, a saw clamping means associated therewith, a swaging die operatively mounted in said block and having a flattened portion adapted to be initially engaged by the face of the tooth to be swaged, and means for initially rotating said die and then to simultaneously rotate and draw said die substantially parallel to and along the face of the tooth to be swaged.

2. A tooth swage including the combination of a swage block, a saw clamping means associated therewith, a swaging die operatively mounted in said block and having a flattened portion adapted to be initially engaged by the face of the tooth to be swaged, means for initially rotating said die and then to simultaneously rotate and draw said die substantially parallel to and along the face of the tooth to be swaged, and means for adjusting the angle at which the flattened portion of said die is initially presented to the face of the tooth.

3. A tooth swage including the combination of a swage block, a saw clamping means associated therewith, a swaging die operatively mounted in said block and having a flattened portion adapted to be initially engaged by the face of the tooth to be swaged, means for initially rotating said die and then to simultaneously rotate and draw said die along a face of the tooth to be swaged, and means for adjusting the plane of travel of said die to coincide with the plane of the face of said tooth.

4. A tooth swage including the combination of a swage block, a saw clamping means associated therewith, a swaging die operatively mounted in said swage block and having a flattened portion adapted to be initially engaged by the face of the tooth to be swaged, means for rotating and drawing the die along the face of the tooth, means for adjusting the angle at which the flattened portion of said die is initially presented to the face of said tooth, and means for adjusting

the plane of travel of said die to coincide with the plane of the face of said tooth.

5. A tooth swage including the combination of a swage block having a swaging anvil adapted to engage the top of the tooth to be swaged, a saw clamping means associated with said swage block, a swaging die operatively mounted within said block and having a flattened portion adapted to be initially engaged by the face of the tooth to be swaged, means for initially rotating said die and then to simultaneously rotate and draw said die along the face of the tooth to be swaged, means for adjusting the angle at which the flattened portion of said die is initially presented to the face of said tooth, and means for adjusting the plane of travel of said die to coincide with the plane of the face of said tooth.

10 6. A tooth swage including the combination of a swage block, a saw blade clamping means associated therewith, a die-carrier slidably mounted in said swage block, a cylindrical swaging die having a flattened section adapted to be initially engaged by the face of the tooth to be swaged, and rotatively mounted in said die-carrier, and a means to first rotate said die and then to simultaneously rotate said die while sliding said die-carrier in said swage block.

15 7. A tooth swage including the combination of a swage block, a saw blade clamping means associated therewith, a die-carrier slidably mounted in said swage block, a cylindrical swaging die having a flattened section adapted to be initially engaged by the face of the tooth to be swaged and rotatively mounted in said die-carrier, and means to first rotate said die and then to simultaneously rotate said die and slide said die-carrier in said swage block, and means for adjusting the angle at which the flattened portion of said die is initially presented to the face of said tooth.

20 8. A tooth swage including the combination of a swage block, a saw blade clamping means associated therewith, a die-carrier slidably mounted in said swage block, a cylindrical swaging die having a flattened section adapted to be initially engaged by the face of the tooth to be swaged and rotatively mounted in said die-carrier, means to first rotate said die and then to simultaneously rotate said die and slide said die-carrier in said swage block, means for adjusting the angle at which the flattened portion of said die is initially presented to the face of said tooth, and means for adjusting the plane of travel of said die and die-carrier to coincide with the plane of the face of said tooth.

25 9. A tooth swage provided with means for giving the swaging die its initial bite, including the combination of a cylindrical swaging die having a flattened portion, means for rotating said die to roll the cylindrical por-

tion of said die into the face of said tooth to give said die its initial bite, and means for adjusting the angle at which the flattened portion of said die is initially presented to the face of said tooth, whereby a predetermined bite is given to said die.

Signed at Loyalton, California, this 24th day of February, 1931.
